FIG. 1

FIG. 2

FIG. 4

FIG. 3

FIGURE 1 is a view in perspective of the portable dishwasher showing our new design;

FIGURE 2 is a top plan view of the portable dishwasher of FIGURE 1;

FIGURE 3 is a side elevational view thereof taken from the left of FIGURE 1; and

FIGURE 4 is a front elevational view thereof.

The rear of the portable dishwasher is substantially plain. The dominant features of our new design reside in the portions shown in full lines.

We claim:

The ornamental design for a portable dishwasher, substantially as shown and described.
